COMBINED TACHOMETER, OIL AND TEMPERATURE INSTRUMENT

John M. Olson, 1513 7th St.,
Port Hueneme, Calif. 93041

Filed Mar. 29, 1973, Ser. No. 345,904

Term of patent 14 years

Int. Cl. D10—04

U.S. Cl. D10—98

Fig. 1

Fig. 2

Fig. 3

Fig. 4

FIG. 1 is an enlarged front elevational view of a combined tachometer, oil and temperature instrument showing my new design;

FIG. 2 is a left front perspective view thereof;

FIG. 3 is a rear elevational view thereof;

FIG. 4 is a right side elevational view thereof.

I claim:

The ornamental design for a combined tachometer, oil and temperature instrument, as shown.
